S.P. Moonhouse,

Lamp Burner.

Patented Apr. 26. 1830.

Stephen P. Moorhouse, Monroe, Michigan.
Sitter's Patent

Dated April 9th 1830.

The Schedule referred to in this Sitter's Patent is making part of the same, containing a description in the words of the said Stephen P. Moorhouse himself of his improvement in the Lamp for burning Sard.

This Lamp differs in nothing from the ordinary tin Jpanned Lamp, than that the
plated copper or some metal containing copper, wire in the top of it & next to the tubes
containing the wicks (around which with the flame plays) this wire being of copper, or
of some metal containing copper, is a good conductor of heat & reaches far down into the
body of the Lamp. The tubes for the wicks are also of copper or of some metal containing
copper. This lamp is constructed for the purpose of burning Sard instead of oil. The
lard being much cheaper producing a more agreeable light. It will keep the lard in
the lamp in a liquid state. Dated April 15th 1830.
